AUTOMATIC PIN-SETTING MACHINE

Charles H. Bauerschmidt, Rochester, N.Y., assignor to
C.H.B. Autobowling Corporation, Rochester, N.Y., a
corporation of New York

Filed Mar. 18, 1953, Ser. No. 722,332

14 Claims. (Cl. 273—43)

The present invention relates to apparatus for automatically setting pins on a bowling alley.

Until very recently there were no automatic pin setters in use; and bowling pins were set either by hand or by so-called semi-automatic pin spotters. There are, therefore, a great number of bowling alleys throughout the country that were built before any automatic pin setters were on the market. The automatic pin setters heretofore available, however, cannot be installed on the conventional bowling alleys, that were built for hand-setting or semi-automatic spotting of pins, without altering those alleys. More space is required at the back of an alley for the mechanism of the previously known automatic pin setters than is required for setting pins by hand or with a semi-automatic pin-spotters. In many cases, to provide this extra space, the back wall has had to be broken out of the building; and a new wall built. This adds expense to the installation of the automatic equipment. Moreover, since it has been the practice in the past to build the backs of the bowling alleys right up to the building lot line, there are many existing bowling alleys in which known automatic pin-setting equipment cannot be installed at all because there is not room enough for it.

Aside from the above-described drawbacks, prior known types of automatic pin-setters are complicated and expensive. Complex mechanisms are required, for instance, to feed the pins automatically to the pin-spotters; and the picking-up and resetting of pins, that have been knocked "off spot," has heretofore involved intricate apparatus. Moreover, the controls, which determine whether a full set, or only part of a set of ten pins, is to be spotted on the alley, are in known types of automatic pin-setting equipment quite complicated. Then, too, in known automatic pins setters quite a large number of bowling pins are required to keep any one machine in operation.

One object of the present invention is to provide an automatic pin setter which can be installed on the conventional alley, which was built for hand-setting or semi-automatic spotting of pins, without alteration of the alley.

Another object of the invention is to provide simple, very accurate mechanism for picking pins up that have been knocked off-spot, and for resetting such pins, after the pins, that have been knocked down, have been swept off the alley, precisely in the off-spot positions which they previously occupied.

Another object of the invention is to provide improved mechanism for picking up the ball and the pins that have been swept off the alley, and for separating the ball from these pins so that the ball may be returned to the front of the alley for reuse, and the pins may be fed forward for resetting.

A still further object of the invention is to provide an automatic pin setting apparatus which will require a minimum number of pins for its continuous operation.

Another object of the invention is to provide an automatic pin setter in which the pin feed mechanism is compact and direct, thereby enabling the apparatus itself to be kept to minimum overall dimensions.

Still another object of the invention is to provide an automatic pin-setter which will be simpler in construction and operation, and less expensive to build than

2

prior types of such automatic equipment and less expensive to maintain.

Other objects of the invention will be apparent hereinafter from the specification and from the recital of the appended claims.

One embodiment of the invention is illustrated in the accompanying drawings. The pin-setting mechanism here shown is put into operation by the rolling of a ball down the alley. The ball drops into a ball elevator or lift in a pit at the rear end of the alley floor. Some or all of the pins, which have been knocked down by the ball, may drop into this lift or elevator also, although most of them will fall into the pin elevator which is disposed in the pit also but which is in front of and under the ball lift.

The weight of the ball trips a switch which starts a motor. If the ball was the first ball of a frame, the motor will send a pin-sensing and pick-up jaws down to sense what pins, if any, have been left standing by the ball. If the ball was the second ball of a frame, ten pin-spotting receptacles will be loaded with a set of ten pins, and will be sent down to spot these pins on the alley. The switch also closes a circuit to a motor that actuates the ball lift so that as the rack, which carries the jaws and the receptacles, starts down, the ball lift starts up. The ball lift comprises essentially a pair of parallel bars which extend transversely of the alley and which are spaced far enough apart to let the pins drop through, back onto the pin elevator, as the ball lift rises, without dropping the ball through. When the ball lift has been raised to its topmost position, it is tilted 90° and the ball is thereby rolled off onto a track which extends to one side of the alley to be returned to the front of the alley ready for use again by the bowler. This track may be like any ordinary ball return track.

There are ten pairs of pin-sensing and pick-up jaws for gripping pins. These pairs of jaws are arranged in a generally triangular fashion to conform to the triangular arrangement in which the pins are set on the alley.

Assuming that the ball, which has been rolled, is the first ball of the frame, and that it has left pins standing, as the rack descends the jaws are closed on the standing pins. The jaws are so mounted on the rack that each pair of jaws will accommodate itself to the position of the particular pin which it is intended to grip. If that pin is off-spot, the jaws will automatically move to the off-spot position of the pin and grip the pin in its off-spot position without changing the position of the pin. Locking means are provided which hold the jaws in the positions to which they have moved in gripping the several standing pins. If there is no pin left standing beneath a particular pair of jaws, the pair of jaws will come together; and the jaws will be locked in that position.

Closing and locking of the jaws completes the sensing operation. The rack then ascends, carrying with it the pins which were left standing and which are now held in the gripping jaws.

The sweep motor is then started, causing the sweep to sweep the pins left on the alley into the pin elevator. The sweep is driven by a crank; and as the sweep starts its return to its starting position, the mechanism for raising the pin elevator is tripped, and this elevator ascends.

At the top of its ascent, the ball elevator is tripped so that it dumps the pins onto a conveyor; whence they are delivered into a guide slot, or pin-positioning track, which will be described further below.

As the sweep approaches the end of its return movement it trips a switch which restarts the motor that operates the rack; and the rack descends again to reset the pins which it previously picked up. The pins are now in place ready for rolling of the second ball of the frame.

The rack is below the pin-positioning track. The ten receptacles or baskets, which it carries, are arranged in triangular fashion corresponding to the triangular arrangement in which the pins are set up on the alley for bowling.

The entering portion of the guide slot or pin-positioning track, into which fallen pins are delivered that are carried up by the elevator, is straight; and this straight portion communicates with an arcuate portion which is almost a complete circle. The pins are carried along this guide slot by their necks, being driven through the straight portion of the slot by an endless belt which extends along one side of this straight portion of the slot.

The outside of the curved portion of the guide slot comprises a plurality of pivotable plates which normally cooperate with the inside wall of the slot to hold the pins in the slot. Stop dogs are pivoted on the inside wall of the slot to space the pins in proper angular relation to one another around the curved portion of the guide slot.

The curved portion of the guide slot will hold eleven pins; and the stops are positioned so that ten of these pins will be disposed so as to be readily dropped into the receptacles or baskets. A circle will pass through six pins of the triangle in which pins are set up on a bowling alley; and these six pins can be dropped directly into their baskets or receptacles. Short chutes are provided to direct the other four pins into their respective baskets or pockets.

When the second ball of the frame is rolled, an electrical circuit will be closed, as soon as the ball drops into the pit, which will start the sweep motor and the elevator motor, bypassing the pin-sensing operation. The ball-lift, which is driven by the elevator motor, will lift the ball as before; and the sweep will be actuated to sweep all the pins off the alley into the pin elevator. The operation will then be as described above, except that, as the sweep approaches the end of its return movement, it will close a circuit to the rack motor and as the racks start down, a cam on the rack shaft will close a circuit to a solenoid that rocks the pivotable plates to release the pins held in the curved portion of the guide slot of the pin feed track, to drop those pins in the pockets or baskets. The rack is then lowered, to set a whole new set of pins on the alley ready for rolling of a new frame.

The pockets or baskets are made in two parts that are pivotally mounted on the rack. The two parts of each pocket or basket are normally locked by a second rack, which is below the first rack, so that they are held in pin-receiving and holding position. However, upon descent of the first rack to pin-spotting position, the second rack will be moved relative to the first rack to release the pocket or basket parts and allow the pins to be spotted on the alley. The jaws, which are used for sensing and picking up pins, will be held in their fully open positions during descent of the first rack for pin-spotting, and will not interfere with the pin-spotting operation.

When a strike ball is thrown on the first ball of a frame, the racks will descend, as in the case first described, where some pins remain standing after rolling of the first ball; but the sensing jaws will not sense any pins and a circuit will be closed that will cause the sweep at the end of its return movement to start the rack motor. Then the solenoid, that rocks the pivotable plates, will be actuated to release the pins from the curved portion of the pin-feed track; and the pin-spotting rack will descend to spot a full set of pins on the alley.

A photo-electric cell may be positioned at the head of the alley to detect if the bowler should cross the foul line. This cell will close a circuit to the sweep; and the operation will be the same from there on as occurs on rolling of the second ball of a frame.

In the drawings:

FIG. 1 is a front elevation of a pin-setting machine built according to one embodiment of the invention, pins being shown in dotted lines; and the sweep being shown fragmentarily and partly in dotted lines also;

FIG. 2 is a plan view of this pin-setting mechanism, part of the sweep being broken away;

FIG. 3 is a side elevation of the pin-setting machine, the alley, and the sweep being shown only fragmentarily;

FIG. 3a is a detail view showing the mechanism for locking the ball-lift against return to its pit position until after the pin elevator has passed the ball-lift in the return movement of the pin elevator to pit position;

FIG. 4 is a fragmentary plan view on a somewhat enlarged scale, showing the feed slot or track through which pins are fed into position above the pin-spotting baskets, ready to be dropped into the baskets;

FIG. 5 is a fragmentary plan view of the feed slot or track showing the pivoted pin-holding plates rocked to pin-releasing positions, but showing the eleventh pin still held in the slot;

FIG. 6 is an enlarged fragmentary section taken on the line 6—6 of FIG. 4 looking in the direction of the arrows;

FIG. 7 is an enlarged fragmentary section taken on the line 7—7 of FIG. 5 looking in the direction of the arrows;

FIG. 8 is a fragmentary plan view showing the chutes for guiding the pins, which are dropped from the guide slot or track, into four of the baskets of the pin-spotting rack, these four pins being shown in dotted lines, the positions of the eleven pins in the guide slot or track, prior to release, also being shown in dotted lines;

FIG. 9 is a plan view on an enlarged scale of the three racks which constitute the sensing and pin-spotting mechanism, parts being broken away for illustrational purposes;

FIG. 10 is a section on the line 10—10 of FIG. 9 looking in the direction of the arrows;

FIG. 11 is a section on the line 11—11 of FIG. 9 looking in the direction of the arrows;

FIG. 12 is a section on the line 12—12 of FIG. 9 looking in the direction of the arrows;

FIG. 13 is a section on the line 13—13 of FIG. 9 looking in the direction of the arrows;

FIG. 14 is a fragmentary side elevation of the three racks in sensing position ready for pick-up off the alley of standing pins, a pair of gripping jaws being shown in full lines in the positions which they assume if there is no pin left standing beneath them to be engaged by them, the gripping jaws being shown also in dash lines in the gripping positions which they assume when there is a pin left standing on-spot beneath them, the pin itself being shown in dotted lines, and the gripping jaws being shown also in dot and dash lines in a typical position assumed for picking up a pin which has been knocked off-spot.

FIG. 15 is a fragmentary side elevation of the three racks, showing the jaws locked in pin-gripping position, ready for pick-up or for resetting of a pin;

FIG. 16 is a fragmentary side elevation of the three racks, showing the jaws in released position after setting of a pin;

FIG. 17 is a fragmentary side elevation of the three racks, showing the racks returned to their uppermost positions, ready for loading with pins;

FIG. 18 is a fragmentary side elevation of the three racks, with the uppermost and intermediate racks so disposed that the pin basket or pocket shown is locked in pin-holding position;

FIG. 19 is a fragmentary plan view of one of the pin baskets or pockets and of the uppermost rack from which it is suspended;

FIG. 20 is an end view of one of the parts of this basket or pocket;

FIG. 21 is a fragmentary view, similar to FIG. 18, but showing the intermediate rack moved relative to the uppermost rack to open the pin basket, spotting the pin on the alley floor;

FIG. 22 is a fragmentary view showing details of the mechanism for raising and lowering the racks to effect sensing and spotting of pins;

FIG. 23 is a side view of the ball elevator;

FIG. 24 is a view showing the belts to which the pins

are delivered from the pin elevator and the spool onto which they are delivered by these belts, and from which they are delivered into the pin guide track;

FIG. 25 is a plan view on a slightly reduced scale showing the ball lift and the pin elevator; and

FIG. 26 is an electrical diagram, showing one way in which the machine may be wired to accomplish its purpose.

Reference will now be made to the drawings by numerals of reference for a more detailed description of the illustrated embodiment of the invention. 30 (FIGS. 1 and 3) denotes the floor of the bowling alley; and 31 are the gutters at the two sides of the alley. The bowling pins are denoted generally at P.

The pin-setting mechanism of this invention is mounted upon a steel framework which comprises a plurality of uprights 35, cross pieces 36, and longitudinally-extending straps 37 (FIGS. 1, 2 and 3) all bolted or welded together to make a strong, rigid support for the operating parts of the mechanism.

Pivotedly mounted on the frame is a shaft 40 (FIG. 3) to which is rigidly secured a pair of arms 41. These arms have telescoping engagement, respectively, with arms 42 that carry at their outer or free ends a plurality of rods 43 (FIG. 2), which are mounted parallel to one another, and which extend transversely across the alley. The rods 43 are of sufficient width to span, the width of the alley 30 and extend over the gutters 31, as clearly shown in FIG. 1. The arms 41, 42 and rods 43 together constitute a sweep. The sweep is driven by a motor 44 through a gear box 34, a shaft 46, a crank arm 47, and a linkage 48, 49, the last-named link being connected to the shaft 40.

As the sweep swings about the axis of shaft 40 it will sweep off the alley and out of the gutters and into the pit 45 (FIG. 3), which is just beyond the rear end of the alley floor, any pins left on the alley 30 or in the gutters 31 after a ball is rolled. As the sweep moves from front to rear and vice versa, pins 57 (FIG. 2) which are carried by arms 42, engage and ride on guides 59 (FIG. 3), that are secured between uprights 35 of the frame, to retract the arms sufficiently for the sweep to follow the horizontal plane of the alley floor.

The floor of the pit 45 is below the level of the floor 30 of the alley. Mounted in the pit are a pin elevator 50 and a ball elevator 51.

The ball elevator 51 comprises a pair of right-angular shaped side plates 52 (FIGS. 3 and 23) and a pair of transverse rods 53 (FIGS. 2, 3, and 25), which are mounted at opposite ends in the side plates and which extend parallel to one another across the width of the alley. These rods are spaced close enough together to support a ball between them, but they are spaced far enough apart to permit pins to drop through between them.

The rods 53 rest in recesses 54 (FIGS. 2 and 25) in the floor of the pin elevator 50, when the ball elevator is in its normal, lower position.

There are rollers 55 secured to the ball elevator 51 which travel in opposed grooves or tracks provided in two bars 56 (FIGS. 3 and 25) mounted in parallelism at opposite sides of the pit.

The ball lift is raised by a pair of cables 58, each of which is secured to the ball lift at one end, and each of which is secured at its opposite end to a drum or pulley 60 (FIGS. 2 and 3) which is secured to a shaft 61 that is rotatably mounted on the frame of the machine to extend transversely thereof. The shaft 61 is adapted to be driven from a motor 63 (FIGS. 1 and 3) through the armature shaft 64, a gear box 62 which drives the shaft 65, a pulley 66 on the shaft, the belt 67, and a pulley 68 which is secured to the shaft 61.

The tracks 56 have upwardly and rearwardly inclined portions for the major portions of their heights, and terminate in portions (denoted at 56' in FIG. 3) which are but slightly inclined to the horizontal. When the motor 63 is actuated to drive the shaft 61 in the direction to wind up the cable 58, the ball lift is raised and when

the rollers 55 reach the portions 56' of the trackways the ball lift 51 is turned ninety degrees as shown in dotted lines in FIG. 3 to dump the ball B off the lift onto the return rails 69 (FIG. 2) which return the ball to the front of the alley. The ball lift is held in its upper position by two catches 38, one on each rail 72, until the pin elevator 50 has been raised and is descending again. These two catches are pivoted on the rails 72 and engage by gravity against the ball lift as shown in FIG. 3. To each catch there is pivoted a trip member 39 (FIG. 3a) which is normally held by gravity in the position shown in FIG. 3a. When the elevator 50 is moving upwardly it will rock the trip members 39 out of the way; but when it is returning to the pit it will engage these trip members causing them through pin 33 to rock the catches up out of the way to release the ball lift, which will then return to the pit by gravity on top of the pin elevator.

Mounted in the pit beneath the ball elevator 51 as shown in FIG. 3, is a limit switch 71 whose purpose is to start the rack motor 250, as will be described further hereinafter. This limit switch is so adjusted that it will not be tripped by the weight of the elevators 50 and 51 alone. However, when a bowling ball drops onto the elevator 51, the extra weight of the ball is sufficient to depress and close the switch 71. When the ball elevator reaches its upper position, it trips a switch 73 (FIG. 3), mounted on one of the rails 56. This de-energizes the clutch solenoid 430 (FIG. 26) as will be described further hereinafter.

The pin elevator 50 is adapted to receive the pins that are knocked into the pit or swept into the pit by the sweep. This elevator carries rollers 70 (FIG. 3) at its rear end which are adapted to travel in the trackways 35 72 (FIGS. 3 and 25) which are disposed at opposite sides of the alley. The elevator 50 is adapted to be lifted by a pair of cables 74, each of which is secured at one end to the elevator, and at its opposite end to a pulley or drum 75 (FIGS. 2 and 3) which is secured to a shaft 76. This shaft is journaled at opposite ends on the upper ends of the rails in which the tracks 72 are formed.

The shaft 76 is adapted to be driven from the shaft 65 through the pulley 81 (FIG. 1), the belt 78 (FIG. 3), and the pulley 79 when a conventional clutch (not shown) connects the drive pulley 81 to shaft 65. This clutch is adapted to be operated by a shift rod 77 (FIG. 3) through a lug 80 (FIG. 2) on the output shaft of gear reduction 34. This lug rocks a lever 47 (FIG. 1) as the sweep motor 44 rotates. This lever is connected by a cable 84 to shift rod 77, as will be described further hereinafter. The pulley 79 (FIGS. 2 and 3) is secured to the shaft 76. As the cables 74 are wound up, upon rotation of the motor 63 after the clutch just mentioned is engaged, the rollers 70 travel in the guideways 72, to the upper position, shown in dotted lines at 50' (FIG. 3). Then due to the curvature of the guideways, the elevator will be tipped so that the pins slide out of the elevator and are discharged therefrom into a chute 88, which delivers them onto an endless belt 82 (FIGS. 2 and 24) whose upper reach runs upwardly from left to right, as viewed in FIG. 2. This endless belt delivers them onto another endless belt 83, the upper reach of which travels transversely of the machine in the opposite direction. The shift rod 77 extends rearwardly far enough to be engaged by pin elevator 50 at the upper limit of travel of the pin elevator to disengage the clutch, permitting the pin elevator to fall back by gravity into the pit.

Belt 83 is driven by a motor 100 (FIGS. 2 and 3) through a gear reduction 101, a shaft 102, a sprocket 103 (FIGS. 2 and 24), a chain 104, and a sprocket (not shown) which is secured to shaft 105. Belt 82 is driven from belt 83 through a pulley and belt drive 106—109—107—108 or any other suitable means. A bar 116

pivottally mounted on the frame is interposed between the two belts 82 and 83, and is rocked up and down by a crank 95 (FIG. 24) and rod 96 to keep the pins from jamming. Crank 95 is secured to the same shaft as that to which gear 109 is fastened.

The belt 83 delivers the pins onto a spool 85 (FIGS. 2 and 24) which has heads or discs at opposite ends that are of large diameter to serve as guides for the pins. Spool 85 cooperates, as shown in FIG. 24, with a rotary plate 86, which is disposed at one end of a chute 90, to erect the pins P and tip them in vertical position into a trackway 110 (FIGS. 2 and 4) formed in a plate 111. Spool 85 has a horizontal axis and disc 86 has a vertical axis. Spool 85 is driven from shaft 105 through a pulley and belt drive 91—92—93. The drive to disc 86 will be described later. The spool 85 serves two purposes: one to guide the pins onto deflector 90 in generally upright position; and the other to pick the pins off belt 83 faster, so that a pin will not be crowded by a following pin on belt 83.

The pins are delivered from deflector 90 into the trackway 110 (FIGS. 2 and 4) formed in a plate 111. The plate 111 is so positioned relative to disc 86 that it is the necks of the pins which will enter trackway 110. The trackway 110 is of a width just sufficient to receive the necks of pins and the pins travel in this trackway and are suspended therefrom by their necks as shown in FIG. 3.

The trackway 110 has a straight entering portion at 117 (FIG. 4), is reversely curved on itself as denoted at 118, and terminates in an almost complete circular portion denoted at 119. One side of the straight portion of the trackway is formed by one side of a slot cut in the plate 111; and the other side of the straight portion of this trackway is formed by a V-belt 112. The pins are rolled along the trackway by action of the moving belt 112. This belt 112 travels around the pulleys 113 and 114. Its slack is taken up by an idler 115; and rollers 116 serve to hold the pin-driving outside lateral reach of the belt in engagement with the necks of the pins.

The belt 112 also forms one side of the reversely curved portion 118 of the guideway, the inside of this reversely curved portion being formed by the belt as it travels about the pulley 114. The outside of this reversely curved portion of the trackway is formed by the outside wall of the slot in plate 111. The belt is driven from shaft 102 (FIGS. 2 and 3) through the bevel gearing 155, shaft 158, and a pair of spur gears 122, the driven member of this pair being secured to the shaft 123 (FIG. 4) of pulley 114. Pulley 113 drives disc 86 through spur gearing 128.

The plate 111 is provided around the outside of the generally circular portion 119 of the trackway 110 with a plurality of spaced arcuate notches or recesses 124 (FIGS. 5 and 4) which are somewhat larger in diameter than the necks of the pins. These notches are equiangularly spaced from one another except for the two notches denoted at 124a and 124b in FIG. 5 which are spaced further apart than the other notches for a purpose which will hereinafter appear.

The portions of the outside wall of the slot between the notches 124 are concentric with axis of a shaft 127 whose function will be described further hereinafter.

Pivottally mounted on top of the plate 111 around the outside of the generally circular slot therein to swing on pins 125 are a plurality of plates or leaves 126. These leaves are adapted to be swung from the positions shown in FIG. 4 to the positions shown in FIG. 5. These leaves have arcuate inside faces 128 which, when the leaves are in the positions shown in FIG. 4, cover the notches 124 and align with the arcuate portions of the outside wall of the slot so that they, in effect, provide, with the outside wall of the slot, an uninterrupted circular outside wall for the trackway which is concentric with axis of shaft 127.

Mounted above the leaves 126 to overlie the same is an

arcuate yoke member 129. This yoke member is oscillatable on plate 111 about the axis of shaft 127. It is held on the plate by guide members 131 (FIGS. 4, 5 and 6) which are secured to the plate by screws 132.

5 The yoke member has a cam surface around its inside face comprising angularly spaced arcuate portions 133 and angularly spaced inclined surfaces 134. Each inclined portion 134 is connected with the next succeeding concentric portion 131 of the yoke by a curved portion 136. The cam portions 133 are concentric with the axis of shaft 127. The leaves 126 carry pins 130 which are adapted to engage and ride on the portions 133 and 134 of the yoke member 125.

15 The inside wall of the approximately circular portion 119 of the track 110 is formed by the nearly circular inside wall 145 of the slot in plate 111, and by dogs 147 which are pivoted by means of pins 148 in the stationary plate 111. Pins 149 are secured in the plate 111 to limit the swinging movement of the dogs 147.

20 As the bowling pins P are fed forward off plate 86 into the track 110 by the belt 112, they drive one another on into the circular portion 114 of this track. They are carried around in this circular portion by the rotating disc 150 (FIGS. 5, 6 and 7) which is disposed beneath 25 dogs 147 and which is secured to shaft 127. This disc is driven from shaft 158 (FIGS. 2 and 4) by a pulley (not shown) on shaft 158, a belt 156, and a pulley 157 on shaft 127.

25 As each pin, traveling in portion 119 of trackway 110, comes in contact with the nose portion 146 of a dog 147, it rocks the dog about its axis 148, to swing the tail portion 151 of the dog outwardly as indicated with reference to the dog 147₁ in FIG. 4. As each pin rolls along the dog, it forces the dog inwardly against the stop 149 associated therewith. When one pin P is in engagement with the tail of a dog 147, another pin cannot swing that dog outwardly. Therefore the nose portions 146 of the dogs act as spacers between the pins.

30 As the pins roll along in track portion 119, also, they ride and push on the arms 441 of normally-closed switches 440. There are three of these switches disposed around the track portion 119. They are so positioned that this track portion must be filled with eleven pins P before all three switches are opened. When they are opened pin 45 feed motor 100 is stopped.

35 The yoke member 129 can be rocked in either direction about the axis of shaft 127 by rocking the arm 149 which is integral therewith, as will be described later. When the pins 130 of the leaves 126 are riding on the portions 133 of the yoke member and the yoke member is in the position shown in FIG. 4, the inside surfaces 128 of the leaves 126 are concentric with axis of shaft 127. When the yoke member is rocked to the position shown in FIG. 5, the grooves 124 are uncovered. This makes a space 50 across the trackway portion 119, abreast of each groove 124, which is wider than the head of a bowling pin, so that all of the bowling pins drop out of the circular portion 119 of the trackway, except for that pin, denoted at X in FIG. 5, which at the time is engaged with the portion 149 of the trackway that lies between grooves 124a and 124b.

55 Mounted on straps 169 (FIGS. 1 and 3), which depend from plate 111, is a plate 161. This plate supports, through the medium of spacers 162, a ring 163 (FIGS. 1, 2 and 8) coaxial with shaft 127 but spaced below plate 111 less than the height of a bowling pin. Secured to the ring 163 to depend therefrom are four chutes 165. Each chute consists of three wire rods 166 together affording a guide down which bowling pins can slide into 60 cups of the setting rack now to be described.

65 When the portion 119 (FIG. 4) of the trackway is full of bowling pins, there are eleven pins in this portion of the trackway, one more pin than required in a set of pins. This makes it possible to drop a whole set of ten pins into the setting rack of the machine without requir- 70

ing more than four chutes 165. The other six pins of the set, arranged as they are in a circle by trackway portion 119, drop readily into their respective pockets in the setting rack. The eleventh pin properly spaces them; and the ring 163 is made slightly larger in outside diameter than the mean diameter of the trackway portion 119 so that all the pins tilt slightly outwardly at their bottoms, as shown in dotted lines in the upper part of FIG. 1, better to drop directly into their cups or pockets in the setting rack, or into their respective chutes and thence into their respective cups or pockets of the setting rack.

FIG. 8 shows in dotted lines how the eleven pins are arranged around the circular portion 119 of trackway 110 and around ring 163. The numerals 1 to 10 applied to the pins denote the respective positions which the pins are to occupy when dropped into the triangular arrangement into which they are required to be disposed when set-up for bowling. X denotes the extra, eleventh pin. Pins numbers 1, 7, 5 and 10 slide down the chutes 165 into cups or pockets in the setting rack. Pins numbers 2, 3, 4, 6, 8 and 9 drop directly into their respective cups or pockets in the setting rack. The extra, eleventh pin is held in trackway portion 119 because there is no groove in the arcuate portion 149 (FIG. 5) of the outside wall of the trackway between grooves or recesses 124a—124b. This extra pin X remains in the trackway after the other ten pins drop from it. It is moved on to the end of the trackway when the next set of pins is fed into the trackway. 1', 7', 5', 10' denote the positions of the No. 1, No. 7, No. 5 and No. 10 pins after they have slid down their respective chutes 165 into their respective cups or pockets in the setting rack.

The setting rack is the uppermost of the three racks, 170, 171 and 172 (FIGS. 1 and 3) used in picking up and setting the bowling pins. Each rack is basically an open framework of generally triangular shape provided with ten rectangular openings 168 as shown in plan in FIG. 9.

Setting rack 170 carries ten cups or pockets 173 arranged in triangular formation corresponding to the triangular arrangement of the bowling pins when set up on the alley. Each cup or pocket comprises two opposed, complementary, generally arcuate socket members 174 (FIGS. 18, 19 and 20) that are pivoted by means of pins 175 in the rack 170. Each of the socket members 174 is normally locked in the position shown in FIG. 18 by lugs or wings 176 which protrude therefrom at opposite ends thereof and which are adapted to engage against shoulders 177 defining the ends of V-shaped notches 178 in the underface of the rack 171.

When the intermediate rack 171 is spaced from the rack 170 as shown in FIG. 18, the cup sockets 174 are held in locked pin-holding position. When the setting rack 170 is moved relatively toward rack 171 to the position shown in FIG. 21 the shoulders 177 of rack 171 disengage themselves from the lugs 176 of the cup sockets and the pins carried in the cups can be set up on the alley.

Mounted on the rack 170 in association with each cup 173 to swing about pivots 180 (FIG. 14) on the rack are two sets of bell-crank members 185. One pair of bell-crank members is mounted on each side of each rectangular opening 168 (FIG. 9) in the rack 170, that is, at each side of each cup or pocket 173. Each bell-crank is connected by means of a pin 186 (FIG. 14) to an arm 187. There are four arms 187 associated with each cup or socket 173, two at each side of each rectangular opening 168 (FIG. 9) in the rack. The aligned arms 187 at opposite sides of each opening 168 carry rubber covered rollers or jaws 188 that are adapted to grip bowling pins that are left standing after the rolling of the first ball of a frame, to lift these pins off the alley.

Each of the jaws 188 projects at opposite ends beyond its rubber covering; and the projecting ends of the jaws are adapted to engage in notches 189 in parallel strap members 190 (FIGS. 9 and 14) that form part of the

bottom rack 172. Swinging movement of the jaws away from one another is limited by pins 194 (FIG. 14) in the arms 185.

The bell-crank arms 185 of each set of gripping jaws 5 are rocked about their respective pivots 174 by links 195 which are connected by means of pins 196 to the members 185, and which are connected by means of pins 197 to cross links 198. Each cross link in turn is connected by means of a pin 199 to a bell-crank 200. Each bell-crank 200 is pivoted on the rack 170 by one of the pins 180, which is associated with its set of gripping jaws. Each bell-crank 200 is connected by means of a pin 201 with a yoke 205.

Each of the three front yokes 205 (FIG. 9) and each 15 of the four rear yokes 205 has a block or cylinder 206 (FIG. 11) secured to it to which there is fastened an angle plate 207. Slidable in each cylinder 206 is a rod 208 which has an enlarged head at its inner end. Interposed between the head of this rod and the projecting 20 end of the cylinder is a spring 209. Secured to the rod by means of an angle plate 210 is a limit switch 212. The free end of the rod 208 is secured by a nut 213 to a lug 214 struck up from a plate 215, which is slidable on uppermost rack 170.

25 A similar structure is used for the three yokes 205 corresponding to No. 4, No. 5 and No. 6 pins (FIG. 9). Here there is attached to each yoke a cylinder 216 (FIG. 12); and there is a rod 217 secured by means of a nut 218 to a lug 219 which projects upwardly from the plate 215. A coil spring 221 is interposed between the projecting end of the cylinder 217 and the yoke 205. The rod 217 passes through the cylinder and has a plate 222 secured to its inner end which engages a limit switch 212. The several limit switches 212 are for determining, after 30 the first ball of a frame has been rolled, whether a whole new set of pins is to be set up, or whether the gripping jaws are to descend again for the purpose of resetting such pins as have been picked up by them, as will be described further hereinafter.

35 40 Pivotedly mounted on a lug 231 (FIG. 10), which projects beneath uppermost rack 170, is a bell-crank lever 232. This bell-crank lever is pivotally connected at its upper end to a link 233 which in turn is pivotally connected to a lug that is welded on the plate 215. A chain 235 connects the bell-crank lever 232 to the lowermost rack 172.

45 A pair of coil springs 240 (FIGS. 9 and 10) constantly urges the plate 215 forwardly of the rack 170. Each coil spring 240 is housed in a cylinder 241 which is welded to the plate 215, and is interposed between the headed inner end of a rod 242 and the projecting end of the cylinder. Each rod 242 is fastened by a screw 243 (FIG. 9) or the like to a plate 244 which, in turn, is secured to the uppermost rack 170.

50 55 After the first ball of each frame of a game is rolled down the alley, the three racks 170, 171 and 172 are lowered so that the jaws 188 can determine whether any pins remain standing or not.

The lowering of the racks is effected by operation of a motor 250 (FIGS. 1 and 3). The armature shaft of this 60 motor carries a pinion 251 which drives a gear 252 on a crank shaft 253. The crank shaft is connected through a connecting rod 254 (FIG. 22) with a link member 256 which carries a pin 257 which engages in a slot 258 in a slide 260. This slide is provided at opposite sides of slot 258 with two longitudinally-spaced rack sections 261 and 262. The rack section 261 meshes with the pinion 263 which is secured to a shaft 265. This shaft in turn carries two axially-spaced pinions 266 (FIGS. 1 and 22) which mesh with racks 268 on two spaced, parallel, vertically sliding bars 267. These bars are secured at their lower ends to the lower-most rack 172, passing through openings in the racks 170 and 171. The rack 262 meshes with the pinion 270 on a shaft 272 (FIG. 1) which is axially aligned with shaft 253 and which is forward of and parallel 70 to shaft 265. The shaft 272 carries a pinion 274 which

meshes with a rack 276, which are secured to a rod 278 that is fastened like the rods 267 to the lowermost rack 172, passing through the racks 170 and 171. The rods 267 and the rod 278 are connected to the rack 172 at the three corners thereof.

The racks 170, 171 and 172 are normally in raised positions; and the rack 170 can be held against movement relative to the rack 171 by a dog 280 (FIG. 14) which engages in a notch in a rod 282 that is secured to the rack 170. The dog 280 is pivoted on a pin 283 in a bracket 284 (FIGS. 3 and 14) that is carried by the rod 278. A coil spring 285, which connects the bracket 284 with the dog 280 through a pin 287, constantly urges the dog 280 to locking position. A solenoid 286, when energized, disengages the dog from the rod 282.

Three dogs 290 (FIG. 14) are provided to limit, at the proper phase in the cycle of operation, upward movement of the lowermost rack 172 relative to the middle rack 171. These dogs are pivotally mounted on pins 292 in rack 170 to engage in notches 291 in the rods 267 and 278. Each dog 290 is moved to operating position by a solenoid 296, and is normally pressed out of operating position by a coil spring (not shown) around the armature of the solenoid.

Rods 298 (FIG. 14) at the three corners of the racks limit the downward movement of the lowermost rack relative to the upper rack. Each rod 298 is adjustably connected by nuts 298' to the uppermost rack 170, and passes through a hole in the middle rack 171, and is secured at its lower end to the lowermost rack 172.

There is also a rod 293 (FIGS. 14 and 15) secured in the lower rack 172 and adapted to pass through the other racks 171, 170. This rod 293 carries a trip member 294 which is positioned to trip a limit switch 315 (FIGS. 14, 15 and 26) for a purpose that will hereinafter be described. Limit switch 315 is secured to uppermost rack 170.

The crank arm 254 (FIGS. 1, 2 and 22) through arm 256, roller 257 and slide 260 not only effects reciprocation of the racks 170, 171 and 172, but also effects movement of ring 129 (FIGS. 4, 5 and 22) to load ten pins into the pin-setting baskets 173 (FIGS. 18 and 21). For rocking ring 129, to drop a set of pins into the ten baskets 173, a lever 300 (FIG. 22) is pivoted at 297 on a lever 299, that is pivoted at 304 on the frame of the machine. Lever 300 has a notch 301 in it that is adapted to engage the roller 257 when the lever 300 is in the position shown in FIG. 22. This lever is moved to engaged position by the armature 302 of a solenoid 303 which is mounted on the frame of the machine. Armature 302 is connected to lever 300 by a spring 306.

A roller 295, that is mounted on an arm 295' which is secured to one of the bars 37 of the frame, engages a cam surface 309 on the undersurface of lever 300, and serves to lift the lever out of engagement with roller 257, when the slide 260 is moved from left to right in FIG. 22. Thus, notch 301 of lever 300 is engaged with roller 257 only long enough in a cycle for the crank-driven arm 256 to pull lever 300 far enough to rock arm 299 to cause yoke 129 to move to the position shown in FIG. 5 to drop a set of pins into the baskets 173 (FIG. 18). A spring 289, which is attached at one end to the lever 299 and at its other end to the frame, serves to restore the yoke 129 to the position of FIG. 4.

A spring 317 serves to pull lever arm 300 clear up out of the way of roller 257 when solenoid 303 is deenergized. This spring is connected at one end to lever 300 and at its opposite end to the frame of the machine.

When the lever 300 is lifted out of engaged position, the pin 257 of arm 256 is free to travel in the slot 258 in the slide 260 between the limits of a solenoid-operated stop 305 and the front wall 308 of the slot 258, if stop 305 is in operative position. If stop 305 is out of operative position, then roller 207 is free to travel the full length of slot 258. The stop 305 can be lifted out of position by energizing the solenoid 307. The stop is secured to the arma-

ture of this solenoid. When stop 305 is in operative position, slide 260 is driven throughout a greater portion of the operating cycle of crank arm 254 than when stop 305 is out of operative position. Stop 305 is moved to operative position when rack 172 is to be moved to its lowermost position for setting a new set of pins on the alley. Stop 305 is in operative position as the rack 172 descends to the position shown in FIG. 14 for sensing what pins, if any, are left standing after the rolling of the first ball of a frame; and if there are pins left standing, stop 305 is pulled out of operative position by energization of solenoid 307, for picking up those pins.

When the apparatus is in its idle position arm 256 is horizontal and is aligned with crank arm 254 which is also horizontal. When the first ball of the frame is rolled, the rack motor 250 starts, but crank 254 traveling counterclockwise as viewed in FIG. 22, does not drive slide 260 at this time. The rods 267 and 278 (FIGS. 1, 2, 9 and 14) are moved downward by gravity, against the resistance of the trains of gearing between them and the motor 250. Thus, the rack 172 is lowered to sense and to pick up any pins that may remain standing. The rod 282 (FIG. 14) remains in its uppermost position fixed against downward movement by the dog 280. The downward movement of the rack 172 itself is limited by nuts 298' on rod 298 engaging rack 170.

As the rack 172 descends, its weight causes chain 235 (FIG. 10) and bell-crank lever 232 to move the plate 215 toward the plate 244 (FIG. 9) so that yokes 205 (FIG. 14), bell-cranks 200, links 193 and 195, and arms 185 rock the several arms 187 toward one another to cause the jaws 188 to grip any standing pins.

The plate 215 is locked in the position, to which it has been moved, by a lock block 310 (FIGS. 9 and 13). Block 310 is adapted to be lifted into the locking position, as will be described further hereinafter, by a solenoid 311, to the armature of which it is secured. Solenoid 311 is carried by an angle bracket 312 which is fastened to a plate 313 that is welded to rack 170. When the block 310 is lifted from the full line position shown in FIG. 13 to the dotted line position shown in that figure, it gets between plate 215 and bracket 312, and prevents return of plate 215 to its normal position until solenoid 311 is deenergized.

There are, as previously stated, ten sets of gripping jaws 188, one for each bowling pin position. These sets of jaws are disposed in triangular arrangement corresponding to the arrangement of the pins on the alley.

If there is no pin left standing below a particular set of jaws, the two jaws of that set will come completely together as shown in full lines in FIG. 14. If there is a pin left standing below a particular set of jaws and that pin is "on spot" that is, it has remained in the correct position to which it was originally set, the jaws of the set will move toward one another to engage and grip the pin as shown in short dash lines at 188' in this figure. If there is a pin left standing below the particular set of jaws and that pin is off-spot, however, the jaws will, in effect, follow the pin to its off-spot position, and grip it there, as indicated in dash and dot lines at 188" in FIG. 14; jaw 188 nearest the off-spot pin will be stopped by the pin as soon as it engages the pin but the other jaw of the pair will continue to be moved by the actuating linkage until it has engaged the pin. When the crank 254, which drives the rods 267 and 278, reverses the movement of the rods 267 and 278, the rack 172 will be raised to bring the notches 189 into engagement with the projecting ends 314 (FIG. 15) at opposite ends of the jaws 188 to lock the several sets of jaws in the positions which they have assumed, and which are illustrated in full, short dash, and dot and dash lines in FIG. 14.

The stop 290, by engagement with the notch 291 of rod 278, at this stage limits the upward movement of rack 172 and prevents the pin, or pins, which is, or are, being lifted, from jamming the aligned cup, or cups, 173.

The stop 290 is rocked by solenoid 296 into engagement with rod 278 so that the lowermost rack 172 will remain at a predetermined distance below the middle rack 171 until rack 172 is lowered again.

After the sweep arm has swept the pins off the alley, the rack 172 is again lowered to set the pins previously picked up. The rack 172 again is moved down to the position shown in FIG. 14 releasing the pin extensions 314 of jaws 188. Then solenoid 311 (FIG. 13) is de-energized so that plate 215 is free to snap back to its normal position under actuation of springs 241 (FIG. 9). This causes the rods 208 and 216 (FIG. 9) to move yokes 205, bell-cranks 200, links 198 and 195, bell-cranks 185, arms 187 and jaws 188 to the positions shown in FIG. 16. This releases any pins previously lifted by the pairs of jaws, resetting these pins on the alley in exactly the position either "on-spot" or "off-spot," which they occupied after the first ball of the frame had been rolled. The rack 172 is then again raised to uppermost position and the jaws and other parts assume the positions shown in FIG. 17.

On the second ball of a frame, the sweep is actuated first. As the sweep is sweeping all the pins off the alley, solenoid 303 (FIG. 22) is energized to pull arm 360 down to the position shown in FIG. 22. As crank arm 254 revolves then, it pulls arm 360 to the right in FIG. 22, rocking arm 299 about its pivot 304. This swings yoke 129 from the position shown in FIG. 4 to that of FIG 5 to release a full set of ten pins and drop them in the cups or pockets 173 (FIG. 18). As the arm 360 moves to the right, roller 295 lifts it up out of operative position, stopping further swing of yoke 129. A cam 316 (FIG. 1) on the crank shaft 253 trips a switch which de-energizes solenoid 303 and allows spring 317 (FIG. 22) to lift lever 300 and rock lever 299 about its pivot 304. It also trips out the catch 280 (FIG. 14) so that the rack 170 can travel all the way down to the position shown in FIG. 21 to set the full set of pins.

The intermediate rack 171 travels down with the other two racks 170 and 172 in setting the full set of pins but its downward movement is limited by nut 318 (FIG. 21) on rod 319. This nut is adapted to engage a bracket 318' forming part of the frame of the machine, while rod 319 itself is secured at its lower end to rack 171. Nut 318 is so adjusted on rod 319 that toward the end of the downward movement of the racks 170, 171 and 172 the nut 318 will strike bracket 318' and further downward movement of rack 171 will be halted before racks 170 and 172 cease their downward movements. This will cause rack 171 to approach rack 170, as shown in FIG. 21, rocking extensions 176 of socket members 174 out of engagement with shoulders 177 of rack 171, thereby releasing the pins to set them on the floor 30 of the alley.

The rack 172 is then raised again to the position of FIG. 17, carrying the racks 170 and 171 with it. The rack 172 engages the wings 176 (FIG. 21) of cups 173 and through these wings it lifts the rack 171. As the rack 172 ascends, the rollers 320, which are carried by lifting rods 278 and 267, pass through rack 171, and engage under rack 170, lifting this rack with rack 172.

When a strike ball is rolled, that is, when all ten pins are knocked down by the first ball of a frame, the rack 172 also descends as is the case with the first ball of any frame, but since there are no pins left standing on the alley, all ten pairs of jaws 188 come together to the positions shown in full lines in FIG. 14. This causes the solenoids 303 (FIG. 22) and 286 (FIG. 14) to be energized, causing the arm 300 to be rocked down so that arm 256 will pull lever 299, rocking yoke 129 (FIGS. 4 and 5) about the axis of shaft 127, causing a whole new set of pins to be dropped into baskets or cups 173 (FIG. 18), so that as soon as the fallen pins have been swept off the alley, the racks 170, 171 and 172 will descend and set up a whole new set of pins as has been

described above with reference to the setting of pins after the second ball of a frame.

When a set of pins starts down, either after a strike ball or the second ball of a frame, or after a foul ball, 5 any one of the three switches 440 (FIG. 4), which is not tripped by the pins, will start the pin feeding motor 100 (FIGS. 1 and 2), which will feed the pins forward into trackway 110 ready for delivery into the cups.

One way in which the machine may be wired to accomplish its purpose is illustrated diagrammatically in FIG. 26.

L_1 denotes the main line, the so-called "hot" wire.

When a ball is thrown down the alley and drops into the pit, it closes the normally open pit switch 71 (FIGS. 3 and 26). A circuit is then made from ground through the switch 71, the line 321 (FIG. 26), the normally closed contacts 322, the line 323, the normally-closed contact 324, the line 325, the coil 326 of a conventional relay which controls the rack motor 250 (FIGS. 2, 3 and 26), and the line 327 to the main line L_1 .

Energization of the coil 326 closes the normally open contacts 330, 331, 328 of the relay.

The closing of contact 328 closes a circuit from the main line L_1 through line 383, relay coil 384, line 389, line 337, and contacts 328, and line 333 to ground. This energizes the relay coil 384. The energization of the coil 384 closes the contacts 397 and 398. The closing of contact 398 establishes a circuit to the elevator motor 63 (FIGS. 1, 2 and 26) from main line L_1 through the line 405, the line 406, the line 407, and the now-closed contact 398 to ground. The closing of the contact 397 maintains a hold-in circuit from the line L_1 through the line 383, the coil 384, the line 389, the line 338, the now-closed contact 397, the line 399, and the normally-closed switch 408 to ground.

The closing of contact 398 also energizes the coil 430 of a solenoid which operates a clutch (not shown) to engage the drive from shaft 65 (FIG. 3) to pulley 66 that drives the mechanism for raising the ball lift 51 (FIGS. 3 and 23). The circuit to coil 430 is made from ground through the contact 398, the line 407, the coil 430, the normally-closed switch 73 (FIG. 3), and the line 432 to the main line L_1 . This causes the ball to be raised and dumped out. At the end of the ball-lifting operation, the ball lift switch 73 (FIGS. 3 and 26) is opened, breaking the circuit to the lift clutch solenoid 430.

The closing of the contacts 331 starts the rack motor 250, a circuit being made from ground through the line 333, the now-closed contacts 331, and the line 334 to the motor, and the motor being connected by the line 335 with the main line L_1 . The closing of the contacts 330 maintains a hold-in circuit for the relay coil 326 when contact is broken at the pit switch 71. This hold-in circuit is from ground through the line 340, the normally-closed switch 341, the line 342, the now-closed contacts 330, the line 343, the line 325, the coil 326 and the line 327 to the main line L_1 .

Actuation of the rack motor 250 permits the racks 172, 171 and 170 to descend. As the racks descend, the rod 293 (FIG. 14), which is connected to rack 172, closes the switch 315. Also a cam 404 (FIG. 1) closes switch 370. The rack 172 comes down to the half way point of its travel, the sensing point. If a strike ball has been rolled, all of the jaws 188 (FIG. 14) come together. Since the switches 212 (FIGS. 11, 12 and 26) are normally closed, the coil 350 of a conventional relay, which for the sake of identification will here be called the "strike relay," is therefore energized, a circuit being made from ground through the now-closed rack switch 315 (FIGS. 14 and 26), the line 351 (FIG. 26), a now closed switch 510, whose function will be described later, the several switches 212, the line 353, the line 354, the coil 350, the lines 357 and 355, and the switch 356 (FIG. 22) to the line L_1 . This energizes the coil 350, closing the normally-open contacts 360 and 361, and opening the

normally-closed contact 363. Switch 356 is closed by slide 260 (FIG. 22).

Only five of the switches 212 have been shown in FIG. 26 for the sake of convenience, although there are actually ten, one corresponding to each pin.

The rack motor is running all the while, and as soon as sensing is complete, the racks 170, 171 and 172 are raised again to their starting positions, cam 409 (FIG. 1) opens switch 341 breaking the hold-in circuit to the rack coil 326.

When switch 370 is closed, a circuit is made from ground through the switch 370, the line 371, the now-closed contact 361, the line 372, the normally-closed contact 374, the line 375, the coil 377, and the line 378 to the line L₁, energizing coil 377 of a conventional relay. The energization of the coil 377, closes the contacts 380, 381 and 382.

The closing of the contact 381 closes a circuit from ground through the line 385, the line 379, the normally-open switch 386, which is now held closed by a cam 511 (FIG. 1) on the rack shaft 253, the line 387 (FIG. 26), the contact 381, the line 388, and the coil 390 of a conventional relay to the main line L₁. This energizes coil 390.

The closing of the contact 380 closes a hold-in circuit to the coil 377 from the main line L₁, through the coil 377, the line 376, the contact 380, the line 393, and the switch 396, in the position shown in FIG. 26, to ground.

The energization of the relay coil 390 closes the contact 400, starting the sweep motor 44 (FIGS. 1, 2 and 26), the circuit to the sweep motor being from the line L₁ (FIG. 26) through the line 402, the motor 44, the line 403, the contact 400, and the line 385 to ground. The sweep motor drives the sweep 43 (FIGS. 2 and 3) to sweep the pins off the alley.

The closing of contact 382 closes a circuit from ground through line 385, line 391, contact 382, line 337, line 389, coil 384, and line 383 to line L₁. This causes the elevator motor 63 to be started as before described.

As the sweep motor swings the sweep back to its at-rest position, after the sweep has swept the pins into the elevator 50, the lug 80 (FIGS. 1 and 2) on the shaft of gear reduction 34 rocks arm 47, causing cable 84 (FIG. 1) to swing lever 77 (FIG. 3) about its pivot to engage a clutch (not shown) that causes shaft 65 (FIG. 3) to drive shaft 76 (FIG. 2) and raise elevator 50 through cables 74. As it is swung to clutch-engaging position lever 77 will close switch 408.

Elevator 50 is raised to the dotted line position shown in FIG. 3 to dump the pins into hopper 88. When the elevator reaches its top position it rocks lever 77 out of engagement with switch 408 to release the clutch actuated by the lever and to permit switch 408 to open.

On its return stroke, also, the lug 80 (FIG. 2) opens the contact at 394 with the switch 396, and makes contact of switch 396 with the terminal 395. This starts the rack motor 250 again, the relay coil 326 again being energized from the line L₁ through the line 327, the line 325, the line 332, the contact 395, and the switch 396 to ground.

A cam 419 (FIG. 1) on the rack shaft 253 will now have rotated into position to close the switch 410 (FIG. 26); and, since the contacts 363 are now closed, a circuit is made from ground through the switch 410, the line 411, the contact 363, the line 412, the line 413, the coil 414 of a conventional relay, the line 355, and switch 356 to the line L₁. This energizes the coil 414, closing the contacts 415 and 416. The closing of the contacts 415 maintains a hold-in circuit to coil 414 from ground through the line 418, the contact 415, and the lines 412 and 413, coil 414, line 355, and contact 456 to line L₁. The closing of the contact 416 makes a circuit from ground through the switch 420, which has been closed by a cam 316 (FIG. 1) on the rack shaft 253, the line 421 (FIG. 26), the contact 416, the line 422, the coils 424 of the three solenoids 286 (FIGS. 14 and 26), and

through the coil 423 of a solenoid 303 (FIGS. 22 and 26), and line 426 to line L₁. The energization of the coils of solenoids 286 disengages the dogs 280 (FIG. 14) from rods 282, allowing rack 170 to drop with rack 172.

5 The solenoid 303 swings arm 300 (FIG. 22) down so the arm 140 (FIGS. 4 and 5) of the yoke 129 may be actuated to cause a new set of pins to be dropped into the cups 173, with the result that when the rack 172 has descended to its lowermost position it can set a whole new set of pins on the alley.

When the racks start down to set up the pins, any of the switches 440, which is closed (FIGS. 4 and 26), will close the circuit to the pin delivery motor 100 to cause pins to be delivered into trackway 110 (FIG. 4). This 15 circuit is from the main line L₁ (FIG. 26) through the line 442, the line 443, the switches 440, when in dotted line positions of FIG. 26, and the line 444 to ground.

The switches 440 are distributed around the circular portion 119 (FIGS. 4, 5 and 26) of the trackway 110.

20 These switches have arms 441 (FIG. 4). When all eleven pins are in place in the track section 119, the switches 440 (FIGS. 4 and 26) will be moved to the full line positions shown in FIG. 26, shutting off the motor 100 to stop feed of pins to the feed track 110.

25 When the rack 172 gets to the end of its downward stroke it opens the normally-closed switch 356 (FIGS. 22 and 26). One of the cams 409 on the rack shaft 253 then opens the switch 341. This stops the rack motor 250.

30 If not all ten pins are knocked down when the first ball of a frame is rolled, the weight of the ball will trip the switch 71 as in the case of a strike ball, and the motor 250 will send the rack 172 down, also, as in the case of a strike ball, to cause the jaws 188 (FIG. 14) to

35 sense what pins are left standing. The switches 212 (FIGS. 11, 12 and 26) associated with the different pairs of jaws, respectively, will assume closed positions such as shown in full lines in FIG. 26, if a pair of jaws 188 close to the full line position of FIG. 14, but they will 40 assume positions such as shown in dotted lines in FIG. 26 if the pair of jaws 188 associated therewith close upon a standing pin P whether that pin be on-spot or off-spot.

When the racks start down, the switch 370 is closed 45 as previously described, and the circuit to coil 377 of the sweep power control is closed as previously described.

At the start of the bowling game the follower 472 is riding on one of the high spots of a cam 473 so that the switch 455 is closed and switches 456 and 457 are open.

50 As long as one pin is left standing after the first ball of a frame is rolled, the coil of a relay 450 (FIG. 26) of conventional construction, known as an "on and off" relay, will be energized, a circuit being closed from the line L₁ through the line 451, the coil 450, the line 452, 55 whichever switches 212 are in the dotted line positions shown in FIG. 26, the now-closed switch 510, the line 351, and the now-closed switch 315 to ground.

The switch 510 is provided simply to prevent inaccurate registering of the sensing operation. The jaws 188 (FIG.

60 14) are covered with rubber sleeves; and if they come together with sufficient force, when there is no pin between them, they are liable to bounce apart. The jaws then register the presence of a pin even though there is no pin between them. To prevent this, the switch 510 is provided.

A cam 316 (FIG. 1) on shaft 253 holds the switch open momentarily, but long enough, after the racks 170, 171, 172 have moved into sensing position (FIG. 14), for any bouncing to have subsided so that the several pairs of jaws, through yokes 205 and switches 70 212 (FIGS. 11, 12 and 26), will register accurately the presence or absence of pins between them when the cam 316 in its continued rotation permits switch 510 to close.

Energization of coil 450 causes pawl 478 to rotate ratchet wheel 479 a step to rotate four-lobed cam 473 75 ninety degrees. This causes the follower 472 to ride

down into a low spot of cam 473. This closes the contacts 456 and 457 and opens contact 455. The closing of the contact 456, closes the circuit to the spare coil 460 from the line 355 through the line 461, the coil 460, the line 464, the line 462, the contacts 456, and the line 463 to ground. This energizes the coil 460.

The closing of the contact 457, closes a circuit from ground through the line 463, the contact 457, the line 466, and the line 469 to the line L₁ through the coils 467 of the solenoids 311 (FIGS. 9, 13 and 26), the coils of the several solenoids 296 (FIG. 14), and the coil 307 (FIG. 22). This moves the blocks 310 (FIGS. 9 and 13) up into position to prevent full return of the plate 215 (FIG. 9). This locks the jaws 188, which have gripped pins, in gripping position. It also energizes the crank solenoid 307 (FIG. 22) to lift stop 305 out of the way so that roller 257 will move a greater distance in the slot 258 before engaging the left hand wall of this slot. This will enable the rack 172 to remain the proper distance below the rack 170 in the pin-lifting operation. It also energizes the three solenoids 296 (FIGS. 14 and 26) to swing the dogs 290 into locking position to space the lowermost rack from the middle rack 171 so that the pins left standing will not hit the cups 173 when they are lifted off the alley.

When the relay coil 460 is energized, the contacts 475, 476 and 477, which are normally open, will be closed, and the contacts 374 and 322, which are normally closed, will be opened.

The opening of contact 322 breaks the circuit to the rack motor relay 325.

When the racks 170, 171 and 172 ascend with the pins which have been picked up, the cam 511 (FIG. 1) closes the switch 386, closing the circuit to the sweep motor relay 377, as previously described, and the pins on the alley are swept off as before. When the sweep returns, as previously described it restarts the rack motor 250 to lower the racks 170, 171, 172 and to reset the pins which were picked up by jaws 288, that is, the pins which were left standing after the first ball of the frame was rolled. The rest of the operation is as before.

When the racks descend to reset the pins, the circuit previously described is made to coil 450, and the cam 473 is ratcheted forward to bring follower 472 onto another high spot of cam 473, returning contacts 455, 456 and 457 to their starting positions.

When the second ball of a frame is rolled, the dropping of the ball into the pit closes switch 71 (FIGS. 3 and 26), starting elevator motor 63, as described above, to raise the ball lift and dump the ball onto the ball-return rails. It also closes a circuit from ground through switch 71, line 321, line 471, now-closed contact 477, line 375, coil 377, and line 378 to line L₁. This closes contacts 380, 381, and 382 as previously described. This closes a circuit to coil 390 and starts sweep motor 44 as previously described. As the sweep shaft rotates, switch 396 is shifted to make contact at 395, closing a circuit to coil 326. This causes starting of rack motor 250, as previously described. As the sweep returns to its at-rest position, the elevator 50 is raised and dumps the pins as previously described.

The coil 460 remains energized after the first ball of the frame has been rolled, and the pins that were left standing have been reset; and it remains energized after the second ball of the frame has been rolled. Thus contact 476 remains closed. Contact 455 is now closed since follower 472 is on a high spot of cam 473. Thus, a circuit is closed to coil 350 from ground through line 481, contact 476, line 480, contact 455, line 453, line 353, line 354, coil 350, line 357, line 355, switch 356, to line L₁. This energizes coil 350 and closes contact 363.

As the rack motor operates, cam 419 (FIG. 1) on the rack shaft 253 will close switch 410, and since contacts 363 are closed, coil 414 will be energized, as previously described. Cam 316 (FIG. 1) on the rack shaft closes

switch 420, as previously described. This energizes coils 286 and 303, allowing the racks 170, 171 and 172 to drop and causing a new set of pins to drop into cups 173 and to be set on the alley, as previously described.

When the slide 260 has moved far enough for the racks 170, 171 and 172 to set the pins, it opens switch 356 (FIGS. 22 and 26), thereby breaking the circuit to relay coils 350, 460, and 414. The cycle is thus completed.

If there are pins left standing after the last ball of the game has been rolled, the player can set up a whole new set of pins by simply pressing push-button 520 closed. This closes a circuit from ground through line 521, push-button 520, line 522, line 321, contact 322, line 323, contact 324, line 325, coil 326, and line 327 to line L₁ to start the rack motor 250. The machine then goes through its cycle as after the second ball of a frame is rolled, as above described.

In event of a foul, a photoelectric cell makes a circuit to a solenoid or other suitable means (not shown) which closes a switch 491. This energizes the relay coil 490, a circuit being closed from ground through the switch 491, a line 492, the coil 490, and line 493 to line L₁. This closes the normally open contacts 495 and 496, and opens the normally-closed contacts 324.

The closing of the contact 496 starts the sweep motor, the circuit being from ground through the line 497, the contact 496, the line 498, the line 375, the coil 377 of the sweep motor relay, and the line 378 to line L₁.

As the sweep performs its motion, it opens the contact at 394 of the switch 396, and closes the contact at 395. This starts the rack motor down, as previously described. Then through the closed contact 495, the strike relay 350 is energized to set a whole new set of pins. The circuit to the strike relay is from the line 355 through the line 357, the coil 350, the line 354, the line 499, the now-closed contact 495, the line 500, and the line 501 to ground.

Operation

While the operation of the illustrated embodiment of the invention will be understood from the preceding description, it may be briefly summed up here.

Assuming that ten pins have been set up on the alley 39 in their proper positions for start of a game, the mechanism is set into operation when a ball, that is rolled down the alley, drops into the ball lift 51 (FIG. 3). The weight of the ball acting through pin elevator 50 will close switch 71 (FIGS. 3 and 26).

If the ball is the first ball of a frame, this starts the rack motor 250 (FIGS. 1, 2 and 26). It also starts the elevator motor 63 to raise the ball lift 51 (FIGS. 3, 23 and 25) to dump the ball on the ball return rails 69 (FIG. 2). The ball lift is then held in its raised, ball-dumping position by detent 38 (FIGS. 3 and 3a).

At this time, the solenoid 303 (FIG. 22) is deenergized and the lever 300 is raised by spring 317 up out of the position shown in FIG. 22. At this time, also, the solenoid 307 is deenergized; and the crank arms 254 and 256 are horizontal, in line with one another. When the rack motor 250 is started, shaft 253 revolves counter-clockwise, as viewed in FIG. 22, but pin 257 moves in slot 258 without driving slide 260; and it is the weight of the rack 172 which causes it to descend. Rack 170 descends with rack 172 until it is stopped by engagement of stop 280 (FIG. 14) with rod 282. Rack 172 continues to descend, however, until it is stopped by engagement of nuts 298 on rod 298 with rack 170. Rack 171 is held in proper spaced relation with rack 170 by engagement of the wings 176 of receptacles or baskets 173 (FIG. 18) with the notches 178 in rack 171.

As the rack 172 descends from its upper position of FIG. 17 to the position shown in FIG. 14, the two jaws of each pair of gripping jaws 188 will swing toward one another by action of gravity; and by the weight of rack 172, operating through chain 235 and links 232, 233,

The linkage will cause the plate 215 (FIGS. 9 and 10) to be pulled toward plate 244, against the resistance of springs 240, thus causing rods 208 (FIGS. 9 and 15) and yokes 205 (FIGS. 9, 11, 12, 14 and 15) to also push the jaws 188 of each pair toward one another.

As the two jaws 188 of a pair move toward one another, if there is no pin left standing between the pair they will close together to the full line positions shown in FIG. 14. This will cause the switch 212 (FIGS. 9, 11, 12 and 26), which is associated with that particular pair of jaws, to assume the full line position shown in FIG. 26.

If there is a pin standing between the two jaws 188 of a pair of jaws as they move toward one another, however, these two jaws will engage the pin, wherever the pin may be, either "on spot" or "off spot," as shown in dash lines and in dot and dash lines, respectively, in FIG. 14; and the switch 212 (FIGS. 9, 11, 12 and 26) associated with that particular pair of jaws will assume the dotted line position shown in FIG. 26.

If there is any pin standing, the two jaws, which engage that pin, will clamp it, and the solenoids 311 (FIGS. 9, 13 and 26) will be energized to interpose the blocks 310 between slide 215 and the frame, to lock the slide 215 in the position to which it has been pulled by the weight of rack 172. This locks the jaws in gripping engagement with any standing pins, and at the same time locks any switches 212, which have been moved to the dotted line position of FIG. 26 in that position.

At this time coil 450 will be energized through whichever switch or switches 212 is or are in dotted line position of FIG. 26, as described previously, causing pawl 478 to rotate ratchet wheel 479 a step to move cam 473 ninety degrees, allowing switch 455 to open and allowing switches 456 and 457 to close.

The rack motor 250 (FIGS. 1 and 26) is, of course, in operation while all this is occurring; and when pin 257 (FIG. 22) reaches the opposite end of the slot 253 in slide 260, the rack motor will raise rack 172 to bring the notches 189 (FIG. 14) up into engagement with the several rods 314 of the different jaw members 188 as shown in FIG. 15, to lock the jaws in clamping engagement with the pins so that, as the several racks ascend, the pins will be lifted off the alley.

Catch 290 (FIG. 15) will engage notch 291 (FIG. 14) in rod 278 to raise rack 170 with rack 172 while maintaining rack 172 a sufficient distance below rack 171 to prevent the pins, which are being lifted, from jamming into the receptacles or baskets 173 and damaging them.

When the racks have ascended far enough so that the pins, which are being lifted, clear the alley floor to the required extent, cam 409 (FIG. 1) on shaft 253 will open switch 341 (FIG. 26) stopping the rack motor 250. At the same time another cam 404 on this shaft will close switch 370 (FIG. 26), starting the sweep motor 44. This will drive the sweep 43 (FIGS. 2 and 3) to sweep off the alley any pins left thereon.

The elevator motor 63 is already running, but the pin elevator 50 (FIGS. 3 and 25) is not raised until the lug 80 (FIGS. 1 and 2) causes lever 77 (FIG. 3) to engage a clutch that causes shaft 65 to raise the pin elevator. When the pin elevator rises its rocks trip 39 (FIG. 3a) idly, leaving detent 38 engaged with ball lift 51. When the pin elevator reaches the dotted line position shown at 50' in FIG. 3 it dumps the pins into hopper 88, and it rocks lever 77 to disengage the elevating drive clutch and to release switch 408 (FIGS. 3 and 26), stopping elevator motor 63. The pin elevator then drops back by gravity into the pit 45 and as it passes trip 39 (FIG. 3a) it rocks detent 38 to release ball lift 51 so that the ball lift returns by gravity also on top of pin elevator 50.

On the return stroke of crank arm 47 (FIG. 2) the lug 80 shifts switch 396 (FIG. 26) to restart rack motor 250. The racks 170, 171 and 172 are therefore again lowered to the position shown in FIG. 14 to reset the pins previously picked up. When the rack 172 has moved down

to this position, the notches 189 drop away from the pin extensions 314 of jaws 188. Then solenoid 311 (FIG. 13) is deenergized so that plate 215 is free to snap back to its normal position under actuation of springs 241 (FIG. 9). This causes the rods 208 and 216 (FIG. 9) to move the linkage 205, 200, 198, 195, 185, 187 and the jaws 188 to the position shown in FIG. 16. This releases any pins previously lifted by the pairs of jaws, resetting these pins on the alley in exactly the "on-spot" or the "off-spot" positions which they occupied after the first ball of the frame had been rolled. The racks 176, 171 and 172 are then again raised to their uppermost positions and the jaws and other parts assume the positions shown in FIG. 17.

When the racks descend coil 450 is again energized, causing ratchet wheel 479 to be advanced again, returning the contacts 455 and 457 to their starting positions shown in FIG. 26.

When the first ball of the frame is a "strike" ball, that is, when all the pins are knocked down by the first ball of the frame, the mechanism is set into operation by the dropping of ball into the pit 45; and again, just as with the first ball of any frame, the rack motor is started to lower the racks to cause the jaws 188 to sense what pins are left standing, and the elevator motor is started to raise the ball lift. Since there are no pins standing, the jaws 188 will come together, and all the switches 212 will assume the positions shown in full lines in FIG. 26. As the rack motor 250 continues in operation, however, it will raise the racks 170, 171, 172 just as has been described in the case where pins have been left standing. Again, also, as where pins were left standing, after the rolling of the first ball, when the racks have ascended far enough, the sweep motor 44 will be started to sweep the pins off the alley, and lever 77 will engage the clutch operated thereby to raise the elevator and dump the pins into hopper 88, after which the elevator drops back into the pit and trips detent 38 to allow the ball lift to drop back also. On the return stroke of the crank arm 47 (FIG. 2), which drives the sweep, the lug 80 shifts switch 396 (FIG. 26) to restart the rack motor as before, but this time, however, due to the positions of switches 212, the solenoids 286 (FIGS. 14 and 26) will be energized to disengage the dogs 280 (FIG. 14) from rods 282, allowing rack 170 to drop with rack 172. At the same time, also, solenoid 303 (FIGS. 22 and 26) will be energized to swing arm 300 down so that arm 140 (FIGS. 4 and 5) of yoke 129 will be swung to drop a full set of pins into cups 173 (FIG. 18). Then as pin 257 continues to move to the right (FIG. 22) roller 295 will lift lever 300 out of engagement with the roller 257. Stop member 305, however, which is now in its down position of FIG. 22, will prevent too fast lowering of the rack 172. The solenoids 286 (FIGS. 14 and 26) are at this time energized to allow rack 172 to descend to its lowermost position (FIG. 21). Rod 319 will then cause rack 171 to be moved toward rack 170 to set a whole new set of pins on the alley.

On the second ball of a frame, switch 71 is again tripped by the dropping of the ball into the pit, and ball lift 51 is again raised, but the sweep motor is actuated first to sweep the pins off the alley before the rack motor is started. Then, since the coil 460 remains energized, a circuit is made to strike coil 350, causing the operation from there out to be similar to that which occurs on a "strike" ball. Solenoid 303 (FIG. 22) is energized to pull arm 300 down to the position shown at FIG. 22. As the crank arm 254 revolves then, yoke 129 is swung from the position shown in FIG. 4 to that of FIG. 5 to release a full set of ten pins and drop them into the cups or baskets 173 (FIG. 18); and the racks travel all the way down to the position shown in FIG. 21, to set up the full new set of pins.

It will be seen therefore, that I have devised an efficient automatic pin-setting apparatus which will precisely re-

set pins "on-spot" and "off-spot," and will reset a whole new set of pins when required in the progress of the bowling game. This apparatus is compact, direct-acting, and is of minimum dimensions.

While the invention has been described in connection with a game of ten pins, it is obvious that it may be used also for games of nine-pins, duck-pins, candle pins etc. by suitable arrangement of the baskets, controls etc. to suit the game to be played, as will be clear to those skilled in the art. It will further be understood that while the invention has been described in connection with a specific embodiment thereof, it is capable of further modification, and this application is intended to include any variations, uses, or adaptations of the invention following, in general, the principles of the invention and including such departures from the present disclosure as come within known or customary practice in the art to which the invention pertains, and as may be applied to the essential features hereinbefore set forth or as fall within the scope of the invention or the limits of the appended claims.

Having thus described my invention, what I claim is:

1. Apparatus for setting pins upon a bowling alley, comprising an upper rack and a parallel lower rack, said racks being movable jointly with and independently of one another toward and away from the alley, a plurality of pairs of arms pivotally mounted on said upper rack, the number and positions of said pairs corresponding to the number and generally to the positions of the pins when set upon the alley, the two arms of each pair being pivotally mounted upon the upper rack to swing freely toward and from one another on parallel axes, a jaw member pivotally mounted on the lower end of each arm, the two jaw members of each pair of arms being swingable toward and away from one another about axes parallel to the axes of swing of the arms, means effective to lower the two racks, means for stopping downward movement of the upper rack when said upper rack reaches a predetermined position, means effective thereafter to permit continued downward movement by gravity of the lower rack until the lower rack reaches a predetermined position, and means connecting said lower rack to said arms to move the two jaw members of all the pairs of jaws simultaneously to gripping positions upon said continued downward movement of said lower rack, thereby to cause said jaw members to clamp any pins standing on the alley, means for locking said jaw members in clamping engagement with any standing pins, and means for raising said upper and lower racks to lift off the alley any pins clamped between said jaw members, said locking means being carried by said lower rack and comprising rod-like extensions on said jaw members which extend parallel to the axes of swing of said jaw members, and notches on said lower rack, and wherein said means for raising said racks operates to lift said lower rack upwardly to engage said rod-like extensions in notches of the lower rack before raising the two racks together.

2. Apparatus for setting pins upon a bowling alley comprising an upper rack and a parallel lower rack, said racks being movable jointly with and independently of one another toward and away from the alley, a plurality of pairs of gripping jaws corresponding in number and generally in positions to the number and positions of the pins when set upon the alley, means effective to lower the two racks, means for stopping downward movement of the upper rack when said upper rack reaches a predetermined position, means effective thereafter to produce continued downward movement of the lower rack until the lower rack reaches a predetermined position below the upper rack, means connecting said lower rack to said jaws to move the two jaws of all the pairs of jaws simultaneously toward each other upon said continued downward movement of said lower rack, thereby to

cause said jaws to grip any pins standing on the alley, means connected to each pair of said jaws to register the presence or absence of a pin between each pair of jaws, and means connected to said registering means to lock

- 5 a pair of jaws in pin-gripping position when a pin is registered as being between that pair of jaws, auxiliary means carried by said lower rack for effecting supplementary locking of that pair of jaws in pin-gripping position, means for raising said lower rack a sufficient distance to 10 move said auxiliary locking means into operative engagement with said jaws, and means for thereafter raising said lower and said upper racks to lift off the alley any pins gripped between said jaws, and control means operatively connected to the several pairs of jaws to cause said 15 racks to be relowered, if any pins are gripped between said jaws, to reset said pins on the alley, and means operatively connected to the several pairs of jaws for delivering and setting a complete new set of pins on the alley if no pins are clamped between said jaws.
- 20 3. Apparatus for setting pins according to claim 2 wherein the auxiliary means for locking said pairs of jaws in pin-gripping position comprises rod-like extensions on said jaws which extend parallel to the axes of swing of said jaws, and notches on said lower rack, and wherein 25 said means for raising said upper rack operates to lift said lower rack upwardly to engage said rod-like extensions in notches of said lower rack before raising the two racks together, and means operative upon re-lowering of said lower rack to release said jaws to reset said pins in the 30 positions, either on-spot or off-spot, which said pins occupied when gripped by said jaws.

4. Apparatus for setting pins on a bowling alley, comprising three racks disposed, respectively, one above another, a plurality of pairs of gripping jaws movably mounted 35 on the uppermost rack, a plurality of pairs of socket members also movably mounted on the uppermost rack, each pair of socket members being disposed within a pair of gripping jaws, means effective to lower the three racks until said uppermost rack reaches a predetermined position, means effective thereafter to produce continued 40 downward movement of the lowermost rack while maintaining the intermediate rack at a predetermined distance below said uppermost rack, means operatively connecting the lowermost rack to said gripping jaws to move the two gripping jaws of the several pairs of jaws toward one another upon said continued downward movement of said lowermost rack to grip any pins standing on the alley, means for thereupon raising said lowermost rack to lock 45 said gripping jaws in clamping engagement with any pins between them, control means connected to each pair of said jaws to register the presence or absence of pins from between them, means for thereupon raising all said racks together to lift off the alley any pins engaged between said gripping jaws, means connecting said intermediate rack to 50 said pairs of sockets to open said sockets when said intermediate rack is moved relative to said uppermost rack, means operated by said registering means for depositing a new set of pins in the pairs of sockets if there are no pins between said pairs of jaws and for thereafter lowering 55 all three racks together to a down position in which the uppermost rack, at least, is below the aforesigned predetermined down position of said uppermost rack, and means for thereupon moving the intermediate rack relative to said uppermost rack to release the new set of 60 pins from said pairs of sockets and position them on the alley.

5. Apparatus for setting pins according to claim 4 wherein said control means is operative, if the gripping jaws of one of said pairs clamp a pin, to cause said racks to be relowered until said uppermost rack reaches its first-named predetermined position to reset on the alley the pins picked up.

6. Apparatus for setting pins upon a bowling alley, comprising an upper rack, a lower rack, and an intermediate rack, said intermediate rack being disposed between

said upper and lower racks and being parallel thereto, said racks being movable jointly with and independently of one another toward and from the alley, a plurality of pairs of gripping jaws mounted on the upper rack, the number and positions of said jaws corresponding to the number and generally to the positions of the pins when set upon the alley, the two jaws of each pair of jaws being movable toward and from one another, a plurality of pairs of socket members movably mounted on said upper rack, the two socket members of each pair cooperating to form a pin-holding receptacle, the number and positions of said receptacles corresponding to the number and generally to the positions of the pins when set upon the alley, means on said intermediate rack for locking the two socket members of each receptacle in position to receive and hold a pin, means effective to lower all said racks, means for stopping downward movement of said upper rack when said upper rack reaches a predetermined position, means operatively connecting said lower rack to said upper rack and operative as said lower rack continues to descend, after stoppage of said upper rack, to move said jaws together to grip any pin that may be left standing between them, means operative thereupon to raise said racks again, control means connected to said jaws to deliver into said receptacles a whole new set of pins if there are no pins gripped between said jaws and for thereupon releasing said stopping means and lowering said racks together again, and means for moving said intermediate rack toward said upper rack upon the second lowering movement to unlock said socket members thereby to release pins carried by said receptacles to set the new pins on the alley.

7. Apparatus for setting pins upon a bowling alley comprising an upper rack, a lower rack disposed beneath said upper rack in parallelism therewith, a plurality of pairs of gripping jaws mounted on said upper rack, the number and positions of said pairs corresponding to the number and generally to the positions of the pins when set upon the alley, the two jaws of each pair being pivotally mounted on said upper rack for movement toward and from one another, means effective to lower said racks, means operative to stop said upper rack when it reaches a predetermined position, and means operatively connecting said jaws to said lower rack, and operative as said lower rack continues its descent, after stoppage of said upper rack, to cause the two jaws of each pair to swing to a position to grip any pin standing between them whether off-spot or on-spot, means operative by said lower rack in its descent to lock in pin-gripping position any pair of jaws which has a pin standing between them, means for thereupon raising said lower rack, auxiliary means on said lower rack operative upon raising of said lower rack for effecting supplementary locking of each pair of jaws in any position to which it may have moved, means connecting said lower rack to said upper rack to thereupon raise said upper rack with said lower rack, means operative thereupon to sweep the alley, and means effective thereafter to lower said racks again to reset on the alley each pin gripped between the jaws in the off-spot or on-spot position that the pin occupied when it was initially gripped by the jaws.

8. Apparatus for setting pins upon a bowling alley, comprising an upper rack, a lower rack, a plurality of gripping jaws movably mounted on said upper rack, said gripping jaws being arranged in pairs, the number and positions of said pairs corresponding to the number and generally to the positions of the pins when set upon the alley, a plurality of sockets movably mounted on said upper rack, said sockets being arranged in pairs and each pair constituting a pin receptacle, each receptacle being disposed within a pair of jaws, and the number and positions of said receptacles corresponding to the number and generally to the positions of the pins when set upon the alley, means effective to lower said racks,

means for stopping downward movement of said upper rack when it reaches a predetermined position and for continuing further downward movement of said lower rack a further predetermined distance, means connecting said lower rack to said jaws so that on movement of said lower rack said further predetermined distance, said pairs of jaws are moved together to sense whether any pin is left standing between them, electrically-operated means connected to said jaws to record the presence or absence of a pin between each pair of said jaws, means for raising said lower rack when the recording operation is completed, means carried by said lower rack for engaging said jaws during raising of said lower rack to lock the jaws in the positions which they have assumed during sensing, thereby to grip any pins disposed between the several pairs of jaws, means connecting said lower rack to said upper rack after a predetermined upward travel of said lower rack to raise said upper rack with said lower rack, means for sweeping pins off the alley, means effective to lower said racks again to reset any pins gripped between said jaws when said recording means records the presence of pins between any pair of jaws, and means effective, when said recording means records the absence of pins between said jaws, to supply a whole new set of pins to said receptacles and to lower said racks beyond said predetermined position and said predetermined distance, respectively, to set the new set of pins on the alley.

9. Apparatus for setting pins upon a bowling alley, comprising an upper rack and a parallel lower rack, said racks being movable jointly with and independently of one another toward and from the alley, a plurality of pairs of gripping jaws mounted on the upper rack, the number and positions of said pairs corresponding to the number and generally to the positions of the pins when set upon the alley, the two jaws of each pair of jaws being movable on said upper rack toward and from one another, means effective to lower the two racks, means for stopping downward movement of the upper rack when said upper rack reaches a predetermined position, means operatively connecting said lower rack to said upper rack and operative as said lower rack continues to descend by gravity, after stoppage of said upper rack, to move said jaws together to grip any pin that may be left standing between them, and means also operated as said lower rack continues to descend by gravity, after stoppage of said upper rack, to lock in pin-gripping position any pair of jaws, which has a pin between them, and auxiliary locking means carried by said lower rack and positioned, upon upward movement of said lower rack to engage a pair of jaws, which has a pin between them, to effect supplementary locking of that pair of jaws in pin-gripping position.

10. Apparatus for setting pins upon a bowling alley comprising an upper rack, a lower rack disposed beneath said upper rack in parallelism therewith, a plurality of pairs of gripping jaws pivotally mounted on said upper rack to depend therefrom, the number and positions of said pairs corresponding to the number and generally to the positions of the pins when set up on the alley, means effective to lower said racks, means operative to stop the downward movement of said upper rack when it reaches a predetermined position, means operatively connecting said jaws to said lower rack and operative, after stoppage of said upper rack, to cause the two jaws of each pair to swing to a position to grip any pin left standing between them on the alley, electrically-operated means actuated by each pair of jaws for registering the presence or absence of a pin between the pair of jaws, means actuated by said electrically-operated means, upon presence of a pin between any pair of jaws, to lock that pair of jaws in pin-gripping position, means for thereafter raising said lower rack, auxiliary locking means on said lower rack and operative upon upward movement of said lower rack to engage the

jaws of any pair which have a pin gripped between them to effect supplementary locking of said pin-gripping pair of jaws in pin-gripping position.

11. Apparatus for setting pins as claimed in claim 10, wherein each jaw is pivotally mounted on said upper rack by means of a bell-crank lever that is pivotally mounted on said upper rack, and the two bell-crank levers, which are associated with a pair of jaws, are connected to a pair of links which in turn are connected to opposite ends of a balancing link, a bell-crank lever is connected to said balancing link intermediate the ends thereof, and a pull rod is operatively connected to the last-named bell-crank lever and to said lower rack to move the jaws toward pin-gripping position upon movement of said lower rack downwardly after stoppage of said upper rack.

12. Apparatus for setting pins as claimed in claim 10 wherein means is provided for connecting said upper rack to said lower rack in spaced relation after said auxiliary locking means is in operative engagement with said jaws whereby upon further upward movement of said lower rack, the two racks travel upwardly together.

13. Apparatus for setting pins as claimed in claim 12,

wherein the last-named connecting means is electrically operated when the first-named electrically-operated means registers the presence of a pin between a pair of jaws.

14. Apparatus for setting pins as claimed in claim 12 for limiting upward movement of said lower rack when a pin is gripped between a pair of jaws.
